UNITED STATES PATENT OFFICE

MICHAEL W. McARDLE, OF CHICAGO, ILLINOIS

DESIGN FOR A HEEL REST FOR ELECTRIC IRON

Application filed October 14, 1929. Serial No. 33,030. Term of patent 7 years.

To all whom it may concern:

Be it known that I, MICHAEL W. McARDLE, a citizen of the United States, residing at Chicago, in the county of Cook and State of Illinois, have invented a new, original, and ornamental Design for a Heel Rest for Electric Iron, of which the following is a specification, reference being had to the accompanying drawing, forming part thereof.

In the drawing—

Figure 1 is a rear perspective view of a heel rest for an electric iron showing my new design; and

Figure 2 is an end elevational view of the same.

I claim:

The ornamental design for a heel rest for electric iron, as shown.

MICHAEL W. McARDLE.
